UNITED STATES PATENT OFFICE.

ROBERT E. MORRIS AND JOHN B. MORRIS, OF WICHITA, KANSAS.

MACHINERY FOR MAKING FENCES.

SPECIFICATION forming part of Letters Patent No. 290,699, dated December 25, 1883.

Application filed September 14, 1883. (No model.)

To all whom it may concern:

Be it known that we, ROBERT E. MORRIS and JOHN B. MORRIS, citizens of the United States, residing at Wichita, in the county of 5 Sedgwick and State of Kansas, have invented a new and useful Improvement in Machinery for Making Fences, of which the following is a specification.

Our invention relates to that class of fence-machines wherein wooden or other palings are united by wires to form a continuous fence or web; and it consists in the several parts and combination of parts hereinafter described, and particularly pointed out in the claims.

15 Figure 1 is a top plan view of the machine; Fig. 2, a transverse section through line $x-x$; Figs. 3, 4, 4', and 5 illustrate certain details of the structure. Fig. 6 illustrates a longitudinal vertical section of the machine.

20 All the operating devices are mounted upon a main frame, A, and may be divided for convenience of description into the mechanism for carrying and twisting the wires, the mechanism for adjusting, holding, and pressing the 25 palings prior to and during the process of applying the wire, and the mechanism for feeding and reeling the completed fence.

The twisting-heads B are each provided with two longitudinal conical perforations for guiding and straightening the wire as it is drawn from the reels C. These reels C are mounted upon the same shaft or spindle D that carries the twisting-head B, and revolve therewith. The reels or spools C are made fast to 35 a spindle, d, carrying a spur-wheel, e, and journaled in a frame, f, attached to the spindle D. A spring, g, fastened at one end to the frame f, bears with its other end upon the side or edge of the spool or reel, and operates by friction to determine the tension of the wire and to prevent the reel running ahead as the wire is drawn off. A set-screw (shown in the drawings) is provided for adjusting the tension of the spring. When the supply of wire contained 40 on the spools becomes exhausted, instead of removing them from the machine and rewinding or replacing by fresh spools, they are rewound while in place. This is effected by means of the shaft j and pinion i , rotated 45 by a crank or otherwise, and applied to the

gear on the spindle of any one of the spools. The supports for the shaft j are provided with two or more sets of bearings, in either of which the shaft may be journaled, so that its gear, which is movable longitudinally upon the shaft 55 j , will mesh with the gear on the spool. One of the bearings, j^2 , in the shaft j is mounted upon pivots, so that it may be swung upward to permit the inserting or removal of the shaft, while the other bearing, j^3 , is made open 60 and a pivoted cap-piece arranged to be swung over it, and thus retain the shaft in position.

The several spindles or shafts D are geared together or connected by sprocket and chain gearing, so that when one is rotated by a crank 65 or otherwise they shall all revolve together. Chain-gearing is preferable, in that the lateral adjustment of the spindles may be compensated for by the addition or removal of one or more of the links. The front and rear bearings for 70 the spindles D are arranged for lateral adjustment, so that the position which the wires are to occupy on the palings may be regulated and determined. With this end in view, the bearing-blocks l are mounted upon the cross-rails 75 l' , and provided with clamping-screws l'' , or other well-known devices for holding them in position when once adjusted.

With mechanism such as above described, two or more double strands of wire can readily be applied to the palings or bars in the following manner: A paling or bar being held in front and across the ends of the several twisting-heads, the two wires carried thereby are passed one above and the other beneath the 85 paling and fastened or held together by a twist or otherwise. The heads are then caused to revolve simultaneously, thus twisting the two wires together for any suitable length, the paling being drawn away if the twist is to be a 90 long one. Another paling is then inserted between the wires, between the heads and the twisted portion already formed, and the heads are again caused to revolve in the same or an opposite direction, the same operations being 95 repeated for each additional paling, the wires on the spools or reels being renewed as occasion requires.

The mechanism employed for holding and positioning the palings during the operation 100

of twisting the wires is as follows: Located in front of the twisting-heads, and on a cross-bar, a'' , are two or more pivoted gages, b'' , against which the palings are drawn after the first twist has been made. The gages are pivoted in or carried by frames sliding in ways on the cross-bar a'' , and their position is determined by set-screws c' . The gages themselves are arranged to project nominally above the face of the bar a'' , and they are so pivoted and connected that they may be simultaneously withdrawn from in front of the paling to allow the same to be drawn forward. This is effected by means of a foot-lever, a' , yoke a' , and connections a^5 . A spring or counter-weight serves to keep the foot-lever up and the gages projecting.

Between the gages b'' and the twisting-heads project two bars, c^3 , mounted upon a shaft, c^4 , and operated by a foot-lever, c^5 , through connections c^6 c^7 . These bars c^3 co-operate with the gages to determine the position of each new paling introduced with reference to the one previously fastened and to the twisting-heads. After the wires have been twisted upon a paling, it is drawn forward against the gages, a new paling is then introduced between the wires and the foot-lever c^5 depressed, causing the bars c^3 to press the paling against the twisted wires and in position while the next twist is being completed. The gages being properly adjusted and the bars c^3 being positively and uniformly pressed against each new paling, the parallelism of the fence-palings forming the fence is assured.

In order to more securely fasten the palings between the wires, we have added a hammer or weighted bar, J , which is so arranged that it will drop or press upon the paling, and thus press the surrounding wires against or into the surface of the wood. The hammer J is located above the cross-bar a'' , and is hung upon two pivoted bars, e^2 , adjustable vertically and longitudinally. Upon the cross-bar a'' rest the anvil-blocks a^6 , which are composed of iron or other suitable material, and act as a bed or anvil upon which the paling rests, while the hammer J operates in conjunction therewith to press the wire into the paling. Rubber or spring cushions may be interposed between the bars and hammer-head, to permit the latter to accommodate itself to inequalities in the size and shape of the palings. The hammer is raised by a chain or belt connected at one end to a drum, K , and at the other to a cross-bar uniting the extremities of the levers e^2 ; or it may be raised or lowered, if desired, by a hand or foot lever properly connected. Where it is desired to make the hammer automatic in its operation, the drum K , to which the strap or chain k^2 is attached, is mounted loosely upon a shaft, k^3 . This lifting-drum is connected and released at predetermined intervals, with a wheel or disk, L , connected by a chain-belt or other gearing with a wheel, l' , on one of the spindles D .

The drum K is provided on one side with a notched or perforated disk, k^4 , with which a dog, l' , carried by the wheel L , engages. The dog l' is provided with a flange, l^5 , and is pressed forward into engagement with the notched disk by the spring-flange l^6 . A stationary cam or incline, l^7 , is fastened to the frame, and so arranged that when the wheel L is revolved it will bear against the flange l^5 on the dog l' and withdraw the latter from engagement with the notched disk. The relative size and arrangement of the gears and cam l^7 are such that the hammer will be raised and dropped once or more during the twisting operation, and it may serve as means for indicating the number or sufficiency of the twists given to the wire.

It is obvious that rollers might be substituted for the hammer to perform the pressing operation; but we prefer the latter as in our judgment better suited for the purpose.

The fence or web as it is formed may be drawn from the machine by hand or otherwise. A mechanism found suitable and well adapted for performing this operation is shown in the drawings. It consists of a shaft or reel, M , hung in inclined open bearings m in front of the cross-bar a'' . The end of the fence or web as it comes from the machine is wrapped around this shaft M , which latter is arranged to be rotated, when necessary, by means of a hand or other lever, n , pivoted to the side of the machine, and connected, through lever n' and link n^2 , with the ratchet n^3 , which latter engages with the toothed wheel n^4 , fastened to the end of the shaft M . The ratchet n^3 is pivoted to the link or plate n^2 , fitting loosely on the shaft M , and is held in engagement with the ratchet-wheel n^4 by a spring, n^5 , as shown. A pawl, n^6 , is arranged to prevent back motion.

Beneath the shaft M is a table, N , supported at one side by legs resting upon the floor, and at the other by a support, n^8 , sliding in ways attached to the main frame. The inner edge of the table is lower than the outer, to permit the fence to be wound upon the shaft. When a sufficient quantity has been wound upon the shaft, the lever n^9 , connected to the support n^8 , is depressed, and the roll of fence is lifted up until the shaft is removed from its bearings, when the whole is pushed back and the shaft withdrawn from the roll and replaced in the machine.

Having fully described our invention, what we desire to claim and secure by Letters Patent is—

1. In combination with the twisting-heads, two or more spools or reels mounted upon the same spindle, and provided with gear-wheels and means for rotating them, whereby they may be refilled without removal from the machine, substantially as described.

2. In combination with the reels or spools mounted upon rotating spindles and provided with pinions, the counter-shaft carrying the

- pinion, adapted to engage with the pinion on the spools and rotate the same, substantially as and for the purpose described.
3. In combination with the twisting mechanism, the pivoted gages and means for withdrawing them from the path of the palings, as and for the purpose described.
4. In combination with the twisting mechanism, the adjustable pivoted gages, as and for the purpose described.
5. In a fence-machine, the combination of adjustable pivoted gages and oscillating levers for positioning the palings with twisting mechanism, substantially as and for the purposes set forth.
6. In combination with the pivoted gages, the hammer for pressing the loops upon the palings, substantially as and for the purpose specified.
- 20 7. In combination with the pivoted gages, oscillating levers, and twisting mechanism, the hammer for pressing the loops formed around the palings, and connected means for operating the several devices, substantially as and for the purpose set forth.
- 25 8. In a fence-machine, and in combination with the hammer, the chain and clutch arranged to raise and release the hammer at predetermined intervals, substantially as described.
- 30 9. In combination with the rotating spindle carrying the twisting-head, the clutch mechanism for operating the hammer at predetermined intervals, as and for the purpose specified.
- 35 10. In combination with the winding-shaft and its open bearings, the vertically-adjustable table for raising and supporting the roll, substantially as described.
11. In combination with the cross-bar a'' , 40 the pivoted gages b'' , mounted in adjustable slides, and means for withdrawing the gages from the path of the material as it is drawn from the machine, substantially as described.
12. The hammer J , supported on levers 45 above the cross-bar a'' and operated intermittently by the clutch mechanism, as described.
13. In a fence-machine, and in combination with the hammer, the rotating disk L , geared to the spindle D , and carrying a dog for engagement with the notched wheel in the drum K , the cam ℓ , located in the path of the dog, and arranged to withdraw the latter at predetermined intervals and release the drum, substantially as and for the purpose specified. 55
14. The removable shaft j , carrying a pinion for engagement with the pinion on the spools, in combination with the spools and with the standards projecting above the spools, and provided, the one with a pivotal and the other with open bearings, for the reception of the shaft j , substantially as and for the purpose specified. 60
15. In combination with a winding reel or shaft, the pivoted gages, oscillating levers, and 65 wire twisting and carrying devices, the hammer J , arranged to press the loops while the paling is held against the gages, and connected means for operating the several devices, substantially as described.
